STAPLE ANCHOR

August W. Ihlenfeldt, Wausau, Wis.

Application August 21, 1933, Serial No. 686,066

4 Claims. (Cl. 256—50)

This invention appertains to wire fences and more particularly to novel means for holding the fence wire in position on the fence post.

One of the primary objects of my invention is to provide means for firmly securing wire fences to concrete or like fence posts, whereby neither the fence wire or post will be injured in any way and whereby the fencing can be easily removed, when so desired.

Another salient object of my invention is the provision of novel members anchored in the fence posts with clamps for engaging the fence wire detachably fitted within said members for firmly holding the wire to the post, novel means being also provided whereby accidental displacement of the clamps is positively prevented.

A further important object of my invention is the provision of novel socket members anchored in the fence post for detachably receiving the wire holding members or clamps, said wire holding members embodying resilient legs having locking projections for engaging in keeper openings formed in the walls of the socket members, the socket members carrying sliding locks for engaging between the legs of the wire holding members, so as to hold the legs against movement and thereby prevent displacement of said members.

A further object of my invention is the provision of novel means for operating the locking members or blocks from the exterior of the sockets, whereby said locking members can be moved into and out of locking position to permit the insertion or removal of the wire holding members from the sockets.

A still further object of my invention is to provide a novel wire holding device of the above character, which will be durable and efficient in use, one that will be simple and easy to manufacture and one which can be placed upon the market and associated with a fence post at a small cost.

With these and other objects in view, the invention consists in the novel arrangement, construction and formation of parts, as will be hereinafter more specifically described, claimed and

illustrated in the accompanying drawing; in which:—

Figure 1 is a longitudinal section through one of my improved wire holding means, the section being taken substantially on the line 1—1 of Figure 3 looking in the direction of the arrows.

Figure 2 is a fragmentary vertical section through a fence post, showing one of my improved wire retaining means anchored therein, the wire retaining device being shown in longitudinal section, the section being taken substantially on the line 2—2 of Figure 3, looking in the direction of the arrows.

Figure 3 is a transverse section through one of my improved wire holding members, the section being taken substantially on the line 3—3

of Figure 2, looking in the direction of the arrows.

Figure 4 is a longitudinal sectional view similar to Figure 2, but showing the wire holding clamp in its partially inserted position.

Figure 5 is a side elevation of my improved wire holding device.

Figure 6 is a perspective view of the same showing the opposite side thereof from Figure 5.

Referring to the drawing in detail, wherein similar reference characters designate the corresponding parts throughout the several views, the letter A generally indicates one of my improved fence wire holding devices and B a fence post with which the same can be associated.

The fence post B can be of any preferred character and if desired, can be formed of concrete, in which instance, my improved wire holding device is anchored therein during the casting of the post.

Referring more particularly to my fence wire holding device A, the same embodies a socket member 10 and a wire engaging member 30.

The socket member 10 comprises a casing 11 preferably formed from companion sections 12 and 13 which can be connected together by means of rivets 14. The sections of the casing are so formed as to provide a longitudinally extending barrel portion 15 and a longitudinally extending socket chamber 16. The socket chamber 16 gradually narrows toward its forward end and this chamber preferably includes a downwardly and forwardly inclined top wall 17 and a horizontally disposed bottom wall 18. The top wall 17 is provided with a series of spaced openings 19. Similar spaced openings 20 are formed in the bottom wall 18 in advance of the openings 19.

Slidably mounted within the chamber 16 is a slide lock block 21, which is of substantially a wedge shape and the top and bottom edges thereof conform to the configuration of the chamber. The slide block 21 is provided with an inverted T-shaped slot 22 for a purpose, which will be later set forth.

The slide block is moved back and forth within the casing or chamber by a novel mechanism, which includes a feed screw 23 arranged within the barrel 15. The ends of the feed screw are rotatably mounted in the end walls of the casing or socket member and the head of the feed screw is arranged beyond the front end of the casing or socket member, so that the feed screw can be conveniently rotated by the use of a screw driver or like implement. A feed nut 24 is mounted upon the feed screw and this feed nut carries a depending slide arm 25, the lower end of which is in turn provided with right angularly extending fingers 26. These fingers project into the chamber 16 and are received within the inverted T-shaped slot 22 of the slide block 21.

Thus, the slide block is firmly secured to the arm 25 and can be fed back and forth by rotating the screw.

The wire holding member 30 is of a substantially U-shape in side elevation and includes the resilient legs 31 and 32, which are connected together by an arcuate bight portion 33. The terminals of the legs 31 and 32, are provided with substantially right-angularly extending toes 10 or lugs 34, which are adapted to be selectively received within the openings 19 and 20 heretofore referred to.

The leg 31 is formed considerably longer than the leg 32 and this facilitates the initial insertion 15 of the wire holding member within the chamber or socket. Also, the leg 31 is preferably at an angle to the leg 32, so as to conform to the inclination of the top wall 17 of the chamber.

In use of my improved wire fence holding device, the screw 23 is turned so as to feed the 20 slide block 21 to the rear of the casing or socket chamber, as shown in Figure 4 of the drawings, after which the wire holding member 30 is placed over the wire and the legs 31 and 32 are compressed and forced toward one another against their inherent resiliency. When the legs are in this position, the legs can then be inserted within the chamber and the member is positioned in the desired distance and the lugs or toes 34 are sprung 25 into the desired openings 19 and 20.

This will firmly hold the wire against the post and obviously, when it is desired to remove the wire, it is merely necessary to again compress the legs, so as to remove the toes or lugs 34 from the openings 20, after which the wire holding member can be pulled from out of the socket chamber.

In order to prevent accidental displacement of the wire holding member 30 and to firmly lock the same in place, the slide block is fed forwardly 40 by means of the feed screw until the same rides between the legs 31 and 32 into firm contact therewith. This positively prevents the legs from being forced inwardly toward one another and in fact, the wedge shape of the block tends to 45 spread the legs and to bind the same against the walls of the chamber.

When the sockets are imbedded in cement or concrete fence posts, soft metal wires are placed 50 in the openings 19 and 20, so as to prevent the filling up of these openings by the concrete and to form sockets within the concrete to receive the toes or lugs 34. After the concrete has set, a hook-like instrument (not shown) is inserted 55 within the chamber and the soft metal wires are pulled out. One of these wires is shown in dotted lines in Figure 4 of the drawing and the same is indicated by the reference character 29.

From the foregoing description, it can be seen that I have provided a novel and simple device 60 for holding fence wires on concrete and like fence posts.

While I have shown the socket member in the drawing as formed from castings, it is to be understood that the socket member can be made in any desired way and in fact, the same can be constructed from sheet metal bent into the desired form.

Obviously, the use of the device is not limited 70 to fence posts and the same can be used in other concrete or cementitious structures, where wires are to be held.

The adjustment of the staple or wire holding

member 30 permits different sizes of wires to be held and in fact, the device itself can be made in different sizes to permit the same to hold large wires and cables.

One of the main objects of forming the entrance to the socket chamber of a small character is to lessen the possibility of rain, snow and the like within the chamber and thus, the device is protected to a great extent against the elements.

The provision of the long leg and the short leg permits the free insertion of the staple or wire holding member 30 into the small opening.

Changes in details may be made without departing from the spirit or the scope of this invention, but what I claim as new is:—

1. A device for holding fence wire on fence posts comprising a socket member adapted to be carried by a fence post, said socket member having a socket chamber, the opposite walls of which are provided with openings, a substantially U-shaped wire receiving member insertable in the chamber having resilient legs, toes on the terminals of the legs for engaging within the openings, and means slidably mounted in the socket 95 and movable between the legs for preventing movement of the legs toward one another.

2. A device for holding fence wire on fence posts comprising a socket member adapted to be secured to a fence post, the socket member having a socket chamber gradually narrowing toward the forward end thereof, a substantially U-shaped resilient fence wire supporting member insertable within the chamber, and a wedge block movable into binding engagement with the legs 105 for holding said legs against the walls of the chamber.

3. A device for holding fence wire on fence posts comprising a socket member adapted to be carried by a fence post having a socket chamber, 115 said chamber including a bottom wall and a downwardly and forwardly inclined top wall, a resilient substantially U-shaped wire supporting member insertable within the socket chamber, one of said legs being longer than the other of said legs and disposed at an angle thereto for engaging the inclined wall, a slide block mounted within said chamber, and means for sliding the block between the legs of the fence wire supporting member for binding said legs in contact with 125 the walls of the socket chamber.

4. A device for holding fence wire on fence posts comprising a socket member adapted to be carried by a fence post, said socket member including a casing having a longitudinally extending barrel and a longitudinally extending socket chamber narrowing toward its forward end, opposite walls of the socket chamber being provided with a series of spaced openings, a resilient substantially U-shaped fence wire supporting 135 member insertable within the chamber having one of its legs longer than the other, oppositely directed toes formed on the legs for engaging in the openings, a slide block mounted within the socket chamber, a feed screw rotatably mounted 140 in the barrel, a feed nut on the screw, and means connecting the feed nut with the slide block, whereby upon rotation of the screw, the block can be moved longitudinally of the socket chamber between the legs of the wire fence supporting 145 means.

AUGUST W. IHLENFELDT.
